UNITED STATES PATENT OFFICE.

CHARLES B. LEFFERT, OF CHICAGO, ILLINOIS, ASSIGNOR TO UNITED STATES TENT & AWNING COMPANY, OF CHICAGO, ILLINOIS, A CORPORATION OF ILLINOIS.

TENT CONSTRUCTION.

Application filed November 9, 1925. Serial No. 67,713.

To all whom it may concern:

Be it known that I, CHARLES B. LEFFERT, a citizen of the United States, and a resident of Chicago, county of Cook, and State of Illinois, have invented certain new and useful Improvements in Tent Constructions, of which the following is a specification.

This invention relates to improvements in tent constructions and consists of the matters hereinafter described and more particularly pointed out in the appended claims.

One of the objects of the present invention is to provide an improved door arrangement for a tent, which includes two door members 15 of flexible material, one of which is storm proof, and the other of which is insect proof, either of which may be manipulated to close the door opening while the other may be folded to one side and there secured in an 20 out of the way position.

A further object of the invention is to so support the top and bottom parts of the doors that they are substantially taut when in closed position and to provide a pocket 25 at one side of the door opening into which the free margins of the doors may be secured from either the inside or the outside of the tent.

Still another object of the invention is to 30 provide a door arrangement for a tent, wherein the use of snap fasteners are eliminated, which costs less to manufacture, is easier to operate and is more efficient in use for its intended purpose.

These objects of the invention as well as 35 others together with the many advantages thereof will more fully appear as I proceed with my specification.

In the drawings:

Fig. 1 is a perspective view of a tent construction embodying my invention.

Fig. 2 is a fragmentary view in elevation on an enlarged scale of that wall of the tent embodying the door opening and associated 45 door members.

Fig. 3 is a detail vertical section on a further enlarged scale through that wall of the tent embodying the top part of the door opening, as taken on the line 3-3 of Fig. 2.

Fig. 4 is a fragmentary horizontal section 50 as taken on the line 4-4 of Fig. 1.

Fig. 5 is another fragmentary horizontal section as taken on the line 5-5 of Fig. 1.

Fig. 6 is still another horizontal sectional 55 view as taken on the line 6-6 of Fig. 1.

The invention is herein illustrated and described as embodied in a tent of the so-called "umbrella" type but this is to be taken by way of illustration only and not by way of limitation because as will be apparent 60 the invention is also applicable to other types of tents where the peculiar characteristics of the invention make it advantageous to do so.

Referring now in detail to that embodiment of the invention illustrated in the accompanying drawings, 1 indicates as a whole a tent of the umbrella type having a front wall 2, side walls 3-3 and a rear wall 4, and associated triangularly shaped top wall or 70 roof sections 2^a-3^a and 4^a, respectively, all of which are made of a suitable tent fabric. The front, side and rear walls in this instance are inclined upwardly and inwardly and the associated top wall sections, meet at 75 the apex of the tent and is there provided with a grommet 5 to receive the usual pin 6 of the center pole. At the four corners of the tent, at the junction of the wall and roof sections, grommets are provided to receive the hooks 8 associated with the arms on the center pole.

The bottom corners of the tent may be secured to the ground in any suitable manner 85 so that the wall and roof sections are substantially taut. In making up the front wall of the tent, I employ two front wall sections 9 and 10, the outer edges of which are cut to form the inclined corners and the inner margins of which are made parallel 90 but spaced apart to provide a rectangular door opening 11 at the middle of said front wall. If desired a floor fabric may be embodied in the tent and if such be the case, the margins thereof are attached to the bottom 95 margins of the side wall sections. Associated with the inner margin of the front wall section 10 and extending from the top to the bottom on the inside thereof, is a strip of flexible material stitched as at 12 100 to said margin along a line spaced from the edge thereof to form a flap 13, which together with said wall margin defines a pocket 14 along one side of the door opening, as best shown in Fig. 5. Associated 105 with the inner margin of the other front wall section 9 and extending from top to bottom on the inside thereof is another strip of flexible material stitched as at 15 to said margin along a line spaced from the edge 110

thereof to form a flap 13, the purpose of which will later appear. At the top of the door opening, on the outside of the front wall sections is a transversely extending 5 head strip 17 which overlaps at its ends upon and is secured to the top end portions of said front wall sections and is secured along its top edge to the underside of the top wall section 2^a by means of a line of stitching 10 and a reinforcing tape as best shown at 18 in Fig. 3.

The bottom ends of the flaps 13 and 16 are connected together by a transversely extending strip 19 which forms a suitable 15 threshold for the door opening and coacts with the head strip to maintain the margins of said wall sections in their proper relations.

Associated with the door opening 11 are inner and outer doors 20 and 21 respectively, 20 both of flexible material, the inner door being made of an open weave fabric such as bobinet for the purpose of providing ventilation to the exclusion of insects and termed an "insect proof door," and the outer 25 door being made of tent fabric and termed a "storm door". The inner door 20 is stitched along one margin to the margin of the flap 16 and the outer door 21 is stitched to the margin of the front wall 30 section 7 near its edge as best shown in Fig. 5. The top and bottom margins of the inner door have suitably spaced eyelets 22 and 23 therein and the top and bottom margins of the outer door are likewise provided with eyelets 24—25 to receive flexible 35 members in the form of cords for supporting said top and bottom margins of said doors when they are folded back against the associated margin of the wall section and 40 unfolded therefrom to open and close said door opening. A looped cord or cable has one of its portions 27 passed through the eyelets at the top of the inner door from opposite sides of said door while its other 45 portion 28 is passed through the eyelets at the top of the outer door from opposite sides thereof as shown in Fig. 4. The looped cord is so supported as to remove the strain of the doors from the tent fabric adjacent 50 the door opening as follows:—The ends of cord loops provided by the cord portions 27 and 28 extend through rings 29 and 30 respectively, each fixed to one end of an associated tape 31 and 32. The tape 31 55 extends along the inner surface of the top end of the wall section 9 and has its other end secured to the tent fabric near the associated eyelet 7 engaged with one of the pole hooks 8. The other tape passes between 60 the flap 13 and the margin of the wall section 10 near its top and is secured to the tent fabric near the associated eyelet 7 engaged with the other pole hook 8. Thus the looped cord which is drawn taut is secured to the tent fabric at points spaced 65

the margins of the wall sections defining the door opening so that said wall sections will not sag or be pulled out of shape. Said cord is so arranged that its ends are only tied together as shown in Fig. 4 so that should it stretch, this stretch may be taken up and the cord again made taut.

A second looped cord is provided for the bottoms of said door members and said cord includes cord portions 33 and 34, the 70 first passing through the grommets 23 at the bottom of the inner door from opposite sides and the second passing through the grommets at the bottom of the outer door from opposite sides as best shown in Fig. 6. 75 The looped ends of said cord portions, pass through rings 35 and 36, respectively, the ring 35 being fixed to a tape 37 secured in between the flap 16 and the margin of the wall section 9 and the other ring being 80 fixed to a tape 38 secured between the flap 13 of the margin of the wall section 10.

On the inner surface of the inner door, about midway between its top and bottom ends is located a tape 39 stitched to the 90 door, with the stitching stopping short of the free margin of the door. The unsecured end of the tape 39 slides through one end of a snap hook 40 and the free end of the tape carries a ring 41. A cord 42 is fastened 95 to said ring and the free end of this cord is adapted to be tied to a second ring 43 secured to that end of the tape 39 on the fixed margin of the door. A tape 44 is secured to the inner surface of the outer door in a manner as just above described and the free end of the tape slides through one end of a snap hook 45, the extreme free end of the tape carrying a ring 46. One end of a cord 47 is fastened to said ring and its 100 other end is adapted to be tied to a ring 48 on that end of the tape 44, fastened to the margin of the wall section 9. Both hooks 40 and 45 may be snapped upon a ring 49 secured to one end of a short tape 105 section 50 located in the pocket 14. Should the material of the doors sag or stretch they may again be made taut by untying the cords 42 and 47 from the rings 43 and 48, 110 taking up the sag and again retying said cords to the rings 43 and 48, respectively.

Should it be desired to use only the inner door so that the door opening is closed against the entrance of insects but at the same time to permit ventilation the outer door is pushed toward the wall sections 9, 115 sliding upon the cord loop portions 28 and 34 and at the same time folding up against the margin of the wall section to which it is attached, said door being secured in this folded position by inserting a tape 51 secured to the outer surface of the wall section 9, through the ring 46. The inner door is then pulled over so that its free margin 120 enters the pocket 14 and the hook 40 is 125 secured to the tape 51. The door opening is 130

snapped into the ring 49. In this manner even though the door is inclined from the vertical it is supported at not only its top and bottom but also at its middle, so that 5 when used to close the door opening it is taut and smooth. With its free margin arranged in the pocket 14, no insects can enter therethrough and the head strip and threshold strip effectively prevent the entrance of insects from the top or bottom of the door.

When the inner door is not needed it may be folded back against the margin of the wall section 9 and secured thereto in an out 15 of the way position. In stormy weather, the outer door may be used to close the door opening in the manner described in connection with the inner door. With the outer door in its closed position it prevents the 20 entrance of rain, snow or wind about the margins of the door as is apparent. Should it be so desired, both doors may be opened or closed from either the inside or outside of the tent.

25 In connection with the doors, I provide an improved structure, which may be used either as an awning or another closure for the door opening as when the tent is left unoccupied. This structure includes a flap 53 made integral with the top wall portion 2^a and of a width equal the base of the same and of a depth equalling that of the front wall formed by the wall sections 9 and 10.

When used for an awning, it is extended 35 horizontally and its free edge is supported by poles 54, only one of which is shown in Fig. 1. When used to cover the door opening, it is brought into position against the front wall to cover the door opening and is 40 secured thereto in any suitable manner. Said flap being wider than the door opening, it securely seals the same at the sides and being integral with the top wall section presents no seam or ridge at the top of 45 the door opening which will act to collect water in case of rain or snow.

50 My improved construction provides a door arrangement for a tent, the advantages of which are apparent from the foregoing description. While in describing my invention I have referred to many details of construction as well as form, arrangement and location of parts, I do not wish to be limited thereto except as may be pointed out in the 55 appended claims.

I claim as my invention:

1. A tent construction embodying a tent wall having a door opening therein, a door 60 of flexible material secured to said tent wall at one side of said door opening, means at the top and bottom of said door opening providing a sliding bearing for said door which permits the same to fold toward said side of said door opening, and coacting 65 means on said door and on the tent wall at

the other side of said door opening for securing the free margin of said door thereto in a manner closing said door opening.

2. A tent construction embodying a tent wall having a door opening therein, a 70 door of flexible material secured to said tent wall at one side of said door opening, flexible means at the top and bottom of said door opening with which the top and bottom margins of said door are operatively engaged for a sliding guiding bearing which permits said door to fold towards said side of said door opening and coacting means on said door and on the tent wall at the other side of said door 75 opening for securing the free margin of said door thereto in a manner closing said door opening.

3. A tent construction embodying a tent wall having a door opening therein, a door 80 of flexible material secured to said tent wall at one side of said door opening, adjustable flexible means at the top and bottom edges of the door opening with which the top and bottom margins of 85 the door is operatively engaged for a sliding guiding bearing which permits said door to fold toward said side of said door opening and coacting means on said door and on the tent wall at the other side of said door opening for securing the free margin of 90 said door thereto in a manner closing said door opening.

4. A tent construction embodying a tent wall having a door opening therein, a plurality of doors of flexible material secured to said tent wall at one side of the door opening, a looped flexible member at the top and bottom of said door opening, means on the top and bottom of the doors operatively engaged with the said looped flexible member providing a sliding guiding bearing for said doors so that they may be folded toward said side of the door opening, and means for securing the free margins of said doors to the other side of the door opening.

5. A tent construction embodying a tent wall having a door opening therein, a plurality of doors of flexible material secured to said tent wall at one side of the door opening, a looped flexible member at the top and bottom of said door openings, means on said tent wall for adjustably securing said member to said tent wall, the top and bottom margins of said doors having grommets 115 slidable on said looped flexible member so that said doors have a sliding guiding bearing thereon, whereby they may be folded toward said side of the door opening and means for securing the free margins of the doors to the other side of the door opening.

6. A tent construction embodying a tent wall having a door opening therein, a door of flexible material secured to said tent wall at one side of the door opening, means at 125

- the top and bottom of said door opening providing a sliding bearing for said door which permits the same to fold toward said side of the door opening, means providing a 5 pocket extending the length of the other side of the door opening, and coacting means on the free margin of said door and in said pocket for securing said margin in said pocket when the door closes said opening.
- 10 7. A tent construction embodying a tent wall having a door opening therein, a door of flexible material secured to said tent wall at one side of the door opening, adjustable flexible means at the top and bottom of said 15 door opening providing a sliding bearing for said door which permits the same to fold toward said side of the door opening, means providing a pocket extending along the other side of the door opening and coacting 20 means on the free margin of said door and in said pocket for securing said door margin in said pocket when the door closes said opening.
8. A tent construction embodying a tent 25 wall having a door opening therein, two door members of flexible material, one of which permits of ventilation therethrough, secured to said tent wall at one side of the opening; an adjustable flexible member having loop portions upon which the top and 30 bottom margins of the doors are engaged for a folding movement toward said side of the door opening, and means providing a pocket along the other side of the door opening to 35 receive the free margins of said doors when in position to close said opening and means in said pocket adapted to coact with devices carried by the door for securing the free margins of the doors in said pocket.
- 40 9. A tent construction embodying therein, a tent wall having a door opening therein, a flap on one margin of said tent wall along one side of the door opening, a door of bobinet or the like fixed to said flap, a second 45 door of flexible material secured to said tent wall margin, a looped adjustable cord secured at the top and bottom of said door opening, said doors having grommets at their tops and bottoms slidable on said looped adjustable cord, a flap on the margin 50 of the tent wall at the other side of said opening and forming therewith a pocket to receive the free margins of said doors, and means on said door and coacting with devices in said pocket for securing the free 55 margins of said doors in said pockets.
10. A tent construction embodying a tent wall having a door opening therein, a door of flexible material secured to said tent wall along one side of the door opening, flexible 60 means at the top and bottom of said door opening and with which the door is operatively connected for a folding movement toward said side of the door opening, and flexible means on said door adapted to be 65 connected to the margin of the tent wall at the other side of said opening for securing said door thereto, said means being adjustable to keep the door taut when closing said opening.
11. A tent construction embodying a tent wall having a door opening therein, a door of flexible material secured to said tent wall along one side of the door opening, flexible 70 means at the top and bottom of said door opening and with which the door is operatively connected for a folding movement toward said side of the door opening, means on the tent wall at the other side of the opening providing a pocket along said other 75 side of the door opening to receive the free margin of said door when the door is in its closed condition, and flexible means on said door adapted to be connected with a device in said pocket for securing said door therein, said means being adjustable to keep the door taut when closing said opening.
- In testimony whereof, I have hereunto set my hand, this 24th day of October, 1925.
- CHARLES B. LEFFERT.
